UNITED STATES PATENT OFFICE.

EUGÈNE LÉON ECKERLEIN, OF PARIS, FRANCE.

TOILET SEAT.

Application filed November 14, 1923, Serial No. 674,603, and in Great Britain November 18, 1922.

This invention relates essentially to a seat formed of one or a number of sections adapted to set on a toilet or water closet bowl and it provides reinforcing members 5 for uniting the sections or to prevent splitting of the wood parallel with its grain.

The covers for the seats of sanitary appliances as constructed up to the present consist generally of a certain number of 10 pieces of wood cut to the proper size which are simply joined together by the groove and tongue method, or they are doweled or mortised and glued together. It so happens in the majority of cases that they come 15 out of joint by the alternate action of dryness and humidity. Furthermore, if they consist of one or more pieces, this method of construction fails to enable them to withstand the effect of stresses or flexure that 20 will be set up transversely or longitudinally and which tends not only to dislocate the joints but also to break them in the direction of the grain or fiber of the wood.

Now, the seat, closure or cover constituting 25 the subject-matter of the present invention is free from these drawbacks, in virtue of the fact that it comprises an interior reinforcement formed of threaded metal rods which absolutely counteract and resist the 30 disjointing tendency of the parts, and which prevent the rupture or splitting of the wood in the direction of its fiber or grain.

The drawing herewith illustrates by way 35 of example one embodiment of the invention and how it can be carried into practice.

Fig. 1 represents a plan view of a seat embodying this invention.

Fig. 2 is a longitudinal section taken 40 along the line II—II.

Fig. 3 is a side view drawn on a larger 45 scale of one of the threaded metallic rods constituting the interior reinforcement.

The new closure consists of one or a plurality of parts or pieces, e. g., 1, 2, 3, 4 Fig. 50 1, of wood cut to size, shaped, fashioned, or bent, and of any convenient configuration.

These pieces are provided with drill holes, 55 in the middle of their thickness as indicated in Fig. 2, and, preferably, in directions at right angles to the fiber or grain of the wood, as far as this is feasible. Into the holes are screwed metallic rods 5 of a suitable diameter furnished with threads. After the rods are screwed in place the ends are thereupon 60 cut flush with the outer periphery of the seat, closure or lid to render them invisible.

under the coat of paint or varnish which covers the surface of the article once it has been finished.

It is evident that such interior metallic 60 reinforcement not only prevents the component pieces from receding from one another by action of variations in the hydrostatic condition of the ambient or surrounding atmosphere, but it likewise imparts to the 65 assembly a high degree of rigidity at right angles or transversely to the fibers of the wood.

This method, be it well understood, is applicable to the manufacture of closures 70 or covers of any form or shape, dimension and proportion whatsoever in a general way, to all cases where the chief desideratum is to insure stability against longitudinal or transverse strain in a plurality of pieces no 75 matter of what kind.

It must further be noted that the method hereinbefore described can likewise be used in closures or other objects of any sort made 80 of a single piece.

The closure or cover made of reinforced 85 wood is especially adapted for seats of toilets as shown and it includes one or a plurality of pieces of wood, traversed about the middle of their thickness by a metallic reinforcement consisting of threaded rods screwed to engage the holes, as far as possible in the direction at right angles to the fiber of the wood, which rods prevent the 90 component wooden parts from expanding under the influence of atmospheric variations.

As indicated in the drawing in order to further reinforce the forward portion of the seat a pair of threaded rods are screwed into 95 bores extending through the side sections and partly into the intermediate section. These rods are arranged diagonally relative to the forward transverse rod and are 100 screwed in from the outer edge of each section.

Each metal rod is threaded its entire length, so that when a rod is screwed into the bore prepared for it the threads will bite into all the portions of the surrounding 105 wood. In this device, the rod after it is screwed in the bore needs no further adjustment and it will be obvious that by reason of the continuous helical thread engagement with the bore the sections are practically 110 united and cannot draw apart by warping or drying.

I claim:—

1. In a toilet seat means to assemble the seat, threaded rods threaded in one direction to traverse the seat after assembling from side to side of the same, and similar rods partly starting from a side of the same and finishing in the interior of the seat.
2. In a toilet seat means to assemble the

seat, threaded rods threaded in one direction to traverse the seat after assembling, ¹⁰ and means to render the ends of the rods cut flush with the outer periphery of the seat invisible under the coat of paint.

In testimony whereof I have hereunto set my hand.

EUGÈNE LÉON ECKERLEIN.
